UNITED STATES PATENT OFFICE.

OWEN LANNON, OF LEE, MASSACHUSETTS.

DESIGN FOR A PIPE-WRENCH HANDLE.

SPECIFICATION forming part of Design No. 31,141, dated July 4, 1899.

Application filed June 1, 1899. Serial No. 719,043. Term of patent 14 years.

To all whom it may concern:

Be it known that I, OWEN LANNON, a citizen of the United States; residing at Lee, in the county of Berkshire and State of Massachusetts, have invented and produced a certain new and original Design for Pipe-Wrench Handles; and I do declare the following to be a full, clear, and exact description of the invention, such as will enable others skilled in the art to which it appertains to make and use the same.

The invention relates to a new and original design for a pipe-wrench handle; and it consists of the design illustrated in the accompanying drawing, in which the figure is a perspective view.

In the drawing, 1 denotes a shank rectangular in cross-section and gradually increasing in area from its inner to its outer end, where it is formed with a head 2, from which project two parallel arms 3, which are spaced apart

their entire length to form an open slot 4, bounded wholly by the end wall 5 and the adjacent sides 6 and 7 of the arms 3. These arms 3 are provided with transverse alined 25 apertures and have their lower edges perfectly straight and lying in the same plane, while portions of the upper edges are perfectly straight and lie in the same plane, and the remaining portions are curved and are 30 formed with transverse teeth 8.

What I claim is—

The design for a pipe-wrench handle as herein shown and described.

In testimony whereof I have hereunto set 35 my hand in presence of two subscribing witnesses.

OWEN LANNON.
